(57) **CLAIM**

The ornamental design for a device for monitoring fertility, as shown and described.

DESCRIPTION

FIG. 1 is a right side view of a receptacle of the device for monitoring fertility;

FIG. 2 is a top view thereof;

FIG. 3 is a bottom view thereof;

FIG. 4 is a front view thereof;

FIG. 5 is a rear view thereof;

FIG. 6 is a bottom front perspective view thereof;

FIG. 7 is a top front perspective view thereof;

FIG. 8 is a right side view of a combined receptacle and sampling device of the device for monitoring fertility;

FIG. 9 is a top view thereof;

FIG. 10 is a bottom view thereof;

FIG. 11 is a front view thereof;

FIG. 12 is a top front perspective view thereof;

FIG. 13 is a top perspective view of the sampling device of the device for monitoring fertility;

FIG. 14 is a top view thereof;

FIG. 15 is a side view thereof;

FIG. 16 is a bottom view thereof;

FIG. 17 is a front view thereof;

FIG. 18 is a rear view thereof;

FIG. 19 is a top perspective view of the sampling device of the device for monitoring fertility in a first deployed position;

FIG. 20 is a top view thereof;

FIG. 21 is a side view thereof;

FIG. 22 is a bottom view thereof;

FIG. 23 is a front view thereof;

FIG. 24 is a rear view thereof;

FIG. 25 is a top perspective view thereof in a second deployed position; and,

FIG. 26 is a top perspective view thereof in a third deployed position.
